UNITED STATES PATENT OFFICE.

OWEN DAVID LUCAS, OF WESTMINSTER, LONDON, ENGLAND, ASSIGNOR TO M. L.
EXPERIMENTAL LIMITED, OF WESTMINSTER, LONDON, ENGLAND.

SHELL FUSE.

Application filed August 24, 1920. Serial No. 405,659.

(GRANTED UNDER THE PROVISIONS OF THE ACT OF MARCH 3, 1921, 41 STAT. L., 1313.)

To all whom it may concern:

Be it known that I, OWEN DAVID LUCAS, a subject of the King of Great Britain, residing at Vickers House, Broadway, Westminster, in the county of London, England, have invented certain new and useful Improvements in Shell Fuses (for which I have filed a patent application in Great Britain on September 1st, 1916, and which has 10 issued as Patent No. 125,598), of which the following is a specification.

This invention relates to shell fuses of the type which has a piston acted upon by the pressure of the air during the flight of the 15 shell, and its object is to provide a fuse which shall be extremely sensitive and which nevertheless shall be perfectly safe until the shell has travelled some distance from the gun.

20 By my invention I am enabled to obviate the necessity of employing a spring for the purpose of keeping the striker away from the detonator.

According to my invention I form on the 25 front of the striker a head which offers a small area to the resistance of the air, but is preferably designed to cover a large surface of an object against which it strikes, such as the fabric composing the envelope of an airship or the wing of an aeroplane. This head is carried by a stem which passes through 30 a hole in the front of the nose of the fuse and carries a piston which works in a cylinder formed in the fuse and is of an area 35 equal approximately to the area of the head.

Arrangements are made whereby air can pass from the nose to the cylinder in rear of the piston so that the pressure behind the piston may be equal to that on the head 40 whatever may be the velocity of the shell in its passage through the air.

In order to counteract any leakage of air past the stem and past the piston, and in order to give a slight resultant pressure tending 45 to keep the striker forward, I provide one or more holes leading from the front of the cylinder to the curved outer surface of the nose of the shell. These holes are inclined at a suitable angle, say 60°, to the 50 axis of the fuse and terminate in an annular recess cut around the nose so that the travel

of the shell induces a slight vacuum in front of the piston.

Preferably a small hole is drilled through the piston so as to give a constant leak and 55 the size of this hole will determine the position of the striker and the strength of the blow required to move it against the detonator.

Preferably also the striker stem is made 60 hollow so as to supply air to the rear of the piston and a hole is formed in the wall of the stem just behind the head so as to allow of the ready escape of the air in the cylinder when the head is sealed by fabric. 65

The striker is normally held away from the detonator, that is, in its forward position by a split collar situated between the head and the nose of the fuse, and round this split collar is wrapped a tape secured by a safety 70 pin supported by a shearing wire and adapted to unwrap itself owing to the rotation of the shell.

My invention is illustrated by the accompanying drawings, in which Figure 1 is a 75 longitudinal section of a fuse with its safety arrangements (except the tape) in position, Figure 2 is a front view thereof and Figure 3 shows the safety tape.

A is the body of the fuse having formed 80 in it a cylinder B in which works a piston C carried by the striker D the hollow stem E of which passes out through the front of the fuse and carries a head F, which is somewhat like a spoked wheel so as to have a 85 large effective area, while only presenting a small area to the action of the air. G G are two halves of a split collar which is seated on the front of the nose of the fuse and supports the head F. One half of the collar has in its inner flat face a recess H adapted to receive the end I of a tape shown in Figure 3 and formed preferably of soft brass, its other end J being turned back to form a loop which may be filled with solder. 90 When the two halves of the collar have been placed in position the tape is wound round filling a groove K in the collar and is prevented from unwinding by a pin L supported by a shearing wire M in a hole N in 100 the body A. On firing the pin sets back shearing the wire M and this releases the end

- J of the tape, which, owing to the rotation of the shell, unwinds itself and accordingly when the shell has proceeded some distance from the gun the two halves of the collar are thrown off and the striker is left absolutely free. Meanwhile, however, air has entered the cylinder B through the stem E and through a hole O in the striker and the latter therefore floats as it were in the fuse.
- 10 P are holes passing from the front of the cylinder B to a peripheral groove Q on the curved portion of the fuse. The rush of air past this groove causes a slight vacuum in front of the piston and therefore any air which may leak past the stem E or past the piston C can escape. R is a small hole drilled through the piston so as to provide a constant leak. S are holes drilled through the wall of the stem just behind the head.
- 15 20 In order that the two halves of the collar may be put on in the correct position and to prevent their rotation, I preferably provide each with a pin T projecting rearwards from it and adapted to be seated in a groove U in the front of the fuse.

A groove V is preferably provided in the set back pin to allow of the escape of the air behind it.

The striker may be adjusted to move back a little way when the collar flies off, and may rest with its point on the surface of the detonator, and it remains in this position until it encounters some object, when the striker is at once driven rearward, the air in the cylinder escaping through the holes S.

It will be seen that this rearward movement of the striker does not depend upon the strength of the blow caused by the material which the fuse meets, but may be looked upon as due rather to the closing by such material of the front of the hollow stem of the striker, owing to which no more air can pass to the rear of the piston, and to the increase, also due to the material, of area of the head, against which area the air now presses, owing to which the air pressure on the head at once overcomes the pressure on the rear of the piston.

It will be noticed that the head F is formed integral with the stem E, and that the piston C is screwed on to the stem. With this construction, should there be any set back on firing, the piston C will strip off the stem, while the striker is held firm, and therefore there can be no premature burst, whereas if the piston were made integral with the striker and the head were screwed on to it, there would be danger of the striker stripping from the head and prematurely exploding the shell.

What I claim and desire to secure by Letters Patent of the United States is:—

1. In a shell fuse, the combination with the striker of a head carried by said striker and arranged in front of the fuse, a cylinder

in the fuse a piston which is carried by said striker and works in said cylinder, the area of said piston being approximately equal to the effective area of said head, and means whereby, during the flight of the shell, air from the front of the fuse acts on the rear face of said piston. 70

2. In a shell fuse, the combination with the striker, of a head made integral with said striker and arranged in front of the fuse, a cylinder in the fuse, a piston which is carried by said striker and works in said cylinder, the area of said piston being approximately equal to the effective area of said head, and means whereby, during the flight of the shell, air from the front of the fuse acts on the rear face of said piston. 75

3. In a shell fuse, the combination with the striker of a head carried by said striker and arranged in front of the fuse, a cylinder in the fuse, a piston which is carried by said striker and works in said cylinder, the area of said piston being approximately equal to the effective area of said head, and means for conveying air from the front of the fuse 80 to the cylinder in rear of said piston. 85

4. In a shell fuse, the combination with the striker of a head carried by said striker and arranged in front of the fuse, a cylinder in the fuse, a piston which is carried by said striker and works in said cylinder, the area of said piston being approximately equal to the effective area of said head, and a passage 90 leading from the front of the fuse to the cylinder in rear of the piston. 95

5. In a shell fuse, the combination with the striker, of a head carried by said striker and arranged in front of the fuse, a cylinder in the fuse, a piston which is carried by said striker and works in said cylinder, the area 100 of said piston being approximately equal to the effective area of said head, the fuse being provided with a rearwardly and outwardly extending hole leading from the front of the cylinder to the exterior of the fuse. 105

6. In a shell fuse, the combination with the striker of a head carried by said striker and arranged in front of the fuse, a cylinder in the fuse, a piston which is carried by said striker and works in said cylinder, the area 110 of said piston being approximately equal to the effective area of said head, means for conveying air to the cylinder in rear of said piston, the fuse being provided with a rearwardly and outwardly extending hole leading from the front of the cylinder to the exterior of the fuse. 115

7. In a shell fuse, the combination with the striker, of a head carried by said striker and arranged in front of the fuse, a cylinder 120 in the fuse, a piston which is carried by said striker and works in said cylinder, the area of said piston being approximately equal to the effective area of said head, the striker being provided with a passage leading from 125

the front of the fuse to the cylinder in rear of the piston, the fuse being provided with a rearwardly and outwardly extending hole leading from the front of the cylinder to the exterior of the fuse.

8. In a shell fuse, the combination with the striker of a head carried by said striker and arranged in front of the fuse, a cylinder in the fuse, a piston which is carried by said 10 striker and works in said cylinder, the area of said piston being approximately equal to the effective area of said head, means for conveying air to the cylinder in rear of said piston, the fuse being provided with a rearwardly and outwardly extending hole leading from the front of the cylinder to the exterior of the fuse, and means whereby a constant leak of air is provided from behind said piston during rearward movement of the latter in the cylinder.

9. In a shell fuse, the combination with the striker of a head carried by said striker and arranged in front of the fuse, a cylinder in the fuse, a piston which is carried by said 20 striker and works in said cylinder, the area of said piston being approximately equal to the effective area of said head, a passage leading from the front of the fuse to the cylinder in rear of said piston, the fuse being provided with a rearwardly and outwardly extending hole leading from the front of the cylinder to the exterior of the fuse and means whereby a constant leak of air is provided from behind said piston during rearward movement of the latter in the cylinder.

10. In a shell fuse, the combination with the striker of a head carried by said striker and arranged in front of the fuse, a cylinder in the fuse, a piston which is carried by said 30 striker and works in said cylinder, the area of said piston being approximately equal to the effective area of said head, the striker being provided with a passage leading from the front of the fuse to the cylinder in rear of the piston, said piston being provided with a hole for providing a constant leak of air from behind said piston during rearward movement of the latter in the cylinder.

11. In a shell fuse, the combination with the striker, of a head carried by said striker and arranged in front of the fuse, a cylinder in the fuse, a piston which is carried by said 40 striker and works in said cylinder, the area of said piston being approximately equal to the effective area of said head, means for conveying air to the cylinder in rear of said

piston, the fuse being provided with a rearwardly and outwardly extending hole leading from the front of the cylinder to the exterior of the fuse said piston being provided 60 with a hole for providing a constant leak of air from behind said piston during rearward movement of the latter in the cylinder.

12. In a shell fuse, the combination with the striker, of a head carried by said striker and arranged in front of the fuse, a cylinder in the fuse, a piston which is carried by said 65 striker and works in said cylinder, the area of said piston being approximately equal to the effective area of said head, and a 70 hollow stem on said striker, said stem conveying air to the cylinder in rear of said piston and being formed with a hole just behind the head.

13. In a shell fuse, the combination with the striker of a head carried by said striker and arranged in front of the fuse, a cylinder in the fuse, a piston which is carried by said 75 striker and works in said cylinder, the area of said piston being approximately equal to the effective area of said head, a split collar for holding the striker in the safe position, a tape wrapped round said collar and a set-back pin for holding 80 said tape in position.

14. In a shell fuse, the combination with the striker of a head carried by said striker and arranged in front of the fuse, a cylinder in the fuse, a piston which is carried by said 85 striker and works in said cylinder, the area of said piston being approximately equal to the effective area of said head, means for conveying air to the cylinder in rear of said piston, a split collar for holding the striker in the safe position, a tape wrapped round 90 said collar and a set-back pin for holding 95 said tape in position.

15. In a shell fuse, the combination with the striker of a head carried by said striker and arranged in front of the fuse, a cylinder in the fuse, a piston which is carried by said 100 striker and works in said cylinder, the area of said piston being approximately equal to the effective area of said head, a passage leading from the front of the fuse to the cylinder in rear of the piston, a split collar for holding the striker in the safe position, a tape wrapped round 105 said collar and a set-back pin for holding said tape in position.

In testimony whereof I affix my signature. 110

OWEN DAVID LUCAS.
